UNITED STATES PATENT OFFICE.

PHILIP F. HOFFMAN, OF NEWBURG, NEW YORK.

DESIGN FOR A NURSING-NIPPLE.

SPECIFICATION forming part of Design No. 33,361, dated October 16, 1900.

Application filed September 18, 1900. Serial No. 30,361. Term of patent 7 years.

To all whom it may concern:

Be it known that I, PHILIP F. HOFFMAN, a citizen of the United States, residing at the city of Newburg, in the county of Orange and State of New York, have invented and produced a new and original Design for a Nursing-Nipple; and I do hereby declare the following to be a clear, full, and exact description of the invention, such as will enable others skilled in the art to which it appertains to make and use the same.

Figure 1 is a perspective view of a nursing-nipple of my new design. Fig. 2 is a central longitudinal sectional view thereof, and Fig. 3 is a top plan view thereof.

As shown in the drawings, the nursing-nipple of my design consists of a hollow ovaloid head A, with a perforation B at one end and at the other end a flaring tubular neck C, merging into an enlarged cylindrical

sleeve D, having an annular external bead E around its bottom edge. Near the upper end of the neck C and in a plane at right angles to the longitudinal axis of the nipple is a five-pointed star F, with solid points, which project beyond the plane of the sleeve D and have their upper faces horizontal and their lower faces inclined.

Having described my invention, what I claim as new, and desire to secure by Letters Patent, is—

The design for a nursing-nipple, as herein shown and described.

In testimony whereof I affix my signature in presence of two witnesses.

PHILIP F. HOFFMAN.
